O. H. SLEEPER.
JEWELRY CLASP.
APPLICATION FILED OCT. 14, 1916.

Patented Oct. 23, 1917.

FIG. 1.

FIG. 2.

Inventor
Otis H. Sleeper
By *Eric G. Goff*.
Attorney

UNITED STATES PATENT OFFICE.

OTIS H. SLEEPER, OF EXETER, NEW HAMPSHIRE.

JEWELRY-CLASP.

1,243,995.

Specification of Letters Patent. Patented Oct. 23, 1917.

Application filed October 14, 1916. Serial No. 125,735.

To all whom it may concern:

Be it known that I, OTIS H. SLEEPER, a citizen of the United States, residing at Exeter, county of Rockingham, State of 5 New Hampshire, have invented certain new and useful Improvements in Jewelry-Clasps, of which the following is a specification.

This invention relates to jewelry clasps, and particularly to a locking device for the 10 pin element of a brooch or the like.

The object of my invention is to provide in a simple, neat and inexpensive construction a pin lock which will positively prevent accidental disengagement of the pin and will 15 be capable of ready manipulation to fasten and unfasten the pin. This object is secured in the device of the present invention.

Briefly, my device consists of a pair of spaced yieldable arms secured to the brooch 20 or other article of jewelry and between which the pin is adapted to be forced and retained by a retaining device consisting in the form shown of a link or ring swiveled to one of the arms and adapted to be engaged 25 with the other arm above the pin to thereby lock the arms together and thus retain the pin in the recess defined by the pair of arms. By this construction any disengaging tendency of the pin is met by the portions of 30 the arm overlying the pin. The upward disengaging pressure of the pin simply tends to spread the arms apart and this tendency is met by the overlying ring which is thereby forced into tight engagement with the pair 35 of locking arms.

The construction and manner of using my device is fully disclosed in the specification which follows. In the drawings, accompanying that specification I have shown a 40 jewelry clasp which has been found satisfactory in use and well adapted to the requirements of manufacture. Throughout this specification and drawings like reference characters indicate corresponding parts.

45 In the drawings:

Figure 1 is a side of a bar pin equipped with a pin lock in accordance with my invention.

Fig. 2 is an end view thereof showing in 50 full lines the locked position of the catch and in dotted lines the open position thereof.

For the purposes of this application I

have illustrated my locking device as applied to a bar pin, although it will be understood that my device may be used with any article 55 of jewelry. I have indicated at 1 the bar of a bar pin. The bar 1 is provided at one end with a pair of spaced ears 2 between which is pivoted at 3 a pin 4. Upon the other end of the bar 1 is mounted my improved pin lock.

This lock consists of a pair of spaced resilient locking arms 5 and 6, between which the pin is adapted to be forced, and a retaining device 7 swiveled to one of said arms 65 and adapted to be swung over and engaged with the other arm to thereby retain the pin between said arms by locking the arms together.

As here shown, the arms 5 and 6 are 70 formed from a single piece of resilient material, preferably spring wire, and are bent into the substantially U-shape shown in the drawings, being soldered or otherwise secured to the bar 1 at the closed portion of 75 the loop. The free end of the arm 6 is bent back upon itself as shown to form an eye 8 in which is swiveled the retainer, which as here shown consists of a simple link or ring 7. The opposite arm 5 is formed at its free 80 end as a locking shoulder 9 under which the ring 7 is adapted to be engaged when the catch is fastened. The arms 5 and 6 are preferably bent to produce opposite portions disposed close enough to each other to be engaged and spread open by the pin in its 85 movement into and out of the recess defined by said arms, (see Fig. 2).

In the use of my device, the pin 4 is forced 90 between the arms 5 and 6, spreading the arms apart in this movement, until it lies in the recess defined by said spaced arms. The inherent resiliency of the arms permits this spreading action and automatically returns the arms to normal position. With the pin 95 thus entered in the locking recess, the ring 7 is swung in the eye 8 to lie transversely across the pin socket and to engage over the upper end of the arm 6 under the shoulder 9 thereof. Any tendency of the pin 4 to disengage from the fastener by spreading apart the arms is therefore met by the overlying ring 7 and this disengaging tendency simply forces the ring farther under the shoul-

der 9 and farther upwardly in the eye 8, thus increasing the tightness of the lock. The upward pressure of the pin in its disengaging tendency is converted into horizontal pressure upon the arms, thereby tending to spread the arms and consequently more firmly retain the locking ring in place. To unfasten the catch and release the pin it is simply necessary to disengage the ring 7 from the shoulder 9. This may readily be effected by pressing the arms 5 and 6 toward each other slightly to shorten the distance between said arms and allow the ring to be disengaged from the shoulder 9, and drop to the position shown in dotted lines in Fig. 2. The pin may then be withdrawn from between the arms 5 and 6 by simply pulling it outwardly away from the bar 1, the arms yielding away from each other slightly as the pin passes the bearing portions thereof. Inasmuch as the material from which the arms 5 and 6 are made is usually cylindrical in cross section, and since the pin is rounded, these bearings offer but little resistance to the movement of the pin in either direction. These bearings, of course, are not depended upon to retain the pin in place, as that is the function of the ring itself.

Various modifications in the form and construction of my device may obviously be resorted to if within the limits of the appended claims.

What I therefore claim and desire to secure by Letters Patent is:

35 1. A pin lock consisting of a pair of spaced members between which the pin is adapted to lie, and an annular retainer swiveled to one of said members and adapted for locking engagement with the other member, and adapted when engaged to prevent separation of the members under the spreading apart tendency exerted against said members by the pin in its disengaging movement.

45 2. A pin lock consisting of a pair of spaced resilient arms between which the pin is adapted to lie, one provided with a locking portion and the other having an eye portion, and a retainer swiveled in said eye portion and adapted for engagement under said locking portion, and adapted when engaged to prevent separation of the arms under the spreading apart tendency exerted against said arms by the pin in its disengaging movement.

55 3. A pin lock consisting of a one piece U-shaped member of resilient material provided with a locking shoulder at one terminus and an eye at its other terminus, and a retaining ring turnably mounted in said eye and adapted for locking engagement with said shoulder.

4. A clasp for use with an article of jewelry having a body portion and a fastening element mounted on said body por-

tion, comprising a U-shaped resilient member secured at the closed portion thereof to the body portion of the article of jewelry, one of the arms of said member terminating in a locking portion, and the other arm 70 terminating in an oppositely disposed eye, and a ring turnably mounted in said eye and adapted to be swung over the space between said arms and engaged with the shoulder to overlie the space between said 75 arms and meet any tendency of the arms to spread apart under the pressure exerted thereagainst by the fastening element in its disengaging movement.

5. A pin lock consisting of a pair of 80 spaced yieldable members between which the pin is adapted to lie, said members having portions disposed toward each other and defining a recess of less width than the cross section of the pin, so that a disengaging 85 movement of the pin exerts a spreading apart tendency upon said spaced members at said opposed portions, and a retaining device carried by one of said members and adapted for detachable engagement with 90 the other member and when engaged to prevent separation of said spaced members.

6. A pin lock consisting of a pair of spaced yieldable members bent to define a recess of less width than the cross section 95 of the pin, and yielding away from each other to permit the pin to be entered in said recess, said portions receiving the pressure of the pin upon a disengaging movement thereof, and said pressure tending to spread 100 apart said members and a retainer swiveled to one of said members above said restricted recess and adapted for locking engagement with the other member and when engaged preventing separation of the said 105 members.

7. A lock consisting of a pair of opposed members yieldable away from each other to permit an element to be locked to be entered therebetween, and automatically returning to normal position after such entry, said members receiving the pressure of the element to be locked upon a disengaging movement thereof, said pressure tending to separate said members, and means to prevent separation of said members upon a disengaging movement of the element to be locked.

8. A lock consisting of a pair of spaced opposed members between which an element 120 to be locked is adapted to be inserted, said members meeting the pressure of the element to be locked upon a disengaging movement thereof in one direction, and means locking said members against the pressure of said element to be locked upon a disengaging movement of said element in one direction.

9. A lock consisting of a pair of spaced opposed members between which an element 125 to be locked is adapted to be inserted, one of

said members having a locking shoulder, and a retainer carried by the other of said members, and adapted for locking engagement with said shoulder and when engaged overlying the space between said members and resisting the unlocking tendency of the element to be locked.

In testimony whereof I affix my signature in presence of two witnesses.
